Application February 25, 1941, Serial No. 380,493

35 Claims. (Cl. 113—38)

This invention relates to improvements in presses, and more particularly to that type of press wherein a die, having the shape and contour of the article to be formed, is used with a pressing member adapted to coact with said die in the pressing operation, the contour of which member, however, is not complementary to the contour of said die but is in the form of a resilient pad which, under pressure, will engage a blank to be processed and press it into the said die to give the blank the desired form of finished article or to give an intermediate form to the blank so that it may, by subsequent operations, be processed into its final form.

The invention is particularly useful in industries wherein the output of products is relatively low in number but the parts going into such products are of a large variety of sizes and shapes. In the production of a single plant in such an industry the total number of completed products put out in a period of time may be relatively low, and each completed article produced might comprise one or only a relatively few of each of a large number of parts of different sizes and shapes. Although the present invention may be useful in numerous industries, the production problems in the aviation industry serve to illustrate the need for the invention. Any given plant in that industry might produce, say, 100 planes per month. In each of those planes there would be hundreds of parts of different sizes and shapes, and each completed plane might possibly embody only one or two of each of such parts. Thus, to satisfy the requirements of one month's production in that plant, it would be necessary to make only 100 to 200 of each of those parts per month. The present invention is considered to be particularly valuable in solving production problems of this character, namely, the production of a large total quantity of numerous parts while producing relatively few of any one part.

Many parts going into completed products are formed by pressing relatively thin and easily deformable material into the desired shapes. If, in producing such parts, the press used is one which accommodates only a single die or pair of dies, it would be necessary to change the dies in the press many times in producing the variety of parts constituting the plant's requirements for a given period of time, such as two weeks or a month. Such a press could be operated quite rapidly only if the dies used therein were designed to produce only one part or an extremely limited number of parts in a single pressing operation. If it were attempted to employ a single

multiple die or a pair of multiple dies adapted to produce a number of different parts therefrom in a single pressing operation, it would probably take one or more operators considerable time, 5 possibly from five to fifteen minutes, to load the die with the proper blanks for each operation, and during the period of that loading operation the press itself would be entirely inactive. On the other hand, if the die used were one which 10 would form only one or two parts in each pressing operation, it would be necessary to change dies many times to produce the numerous different parts required.

An important object of the present invention 15 is the provision of a press having a plurality of die-carriers which may be substituted rapidly for each other, so that, while a die on one carrier is being loaded by one or more operators with the proper blank material, the blanks loaded by 20 other operators onto dies on other carriers may go through the pressing operation, thus keeping the press in substantially continuous operation and affording substantial economy in the production of small numbers of each of a large number 25 of different parts.

Another object of the invention is the provision of means whereby the various die-carriers and dies thereon, loaded with blanks, may be moved into the press for the pressing operation while avoiding any interference of two or 30 more dies with each other during the substitution of dies.

Another object of the invention is the provision of a press having a plurality of radially 35 movable, interchangeable die-carriers and a resilient pressing member for coacting with a die on any one of said die-carriers in a pressing operation, and means whereby the action of the die-carriers and the said pressing member is so interrelated that, although the die-carriers move 40 into and remain in the press in different radial positions, the pressing member, however, is caused to automatically move to a position corresponding to the position of whatever die-carrier 45 is in the press, so that the proper coaction between the die on said carrier and the pressing member may be attained.

Still another object of the invention is the provision of means by which the action of the 50 press in closing and opening is interrelated to the action of the several die-carriers and the movement of the pressing member, so that the desired coaction in the operation of the said parts of the press during a pressing operation is obtained.

Another object of the invention is the provision of means by which radially arranged die-carriers, in such a press, may be caused to move onto the bed of the press, for a pressing operation, in the order in which the dies on said carriers are loaded with blanks ready to be pressed, irrespective of the radial positions of said carriers. In other words, this object is to avoid the necessity, present in numerous types of machine tools, that the several parts referred to must operate in a defined sequence.

Another object of the invention is the provision of operating means for the press which are substantially automatic, and still further objects and advantages of the present invention will be perceived from the following specification and the accompanying drawings.

The objects and advantages of the present invention may be attained in a press having a plurality of die-carriers, radially arranged in a common horizontal plane, each adapted to be moved radially, with a die thereon, to a central point where it may rest upon the bed of the press, and having a pressing member in the form of a resilient pad disposed coaxially relatively to the bed of the press and adapted to coact with a die on any one of said carriers which may be positioned upon the bed of the press, in order to perform a pressing operation.

Inasmuch as several of the radially arranged die-carriers in such a press would be disposed in different radial positions when resting upon the press-bed, the resilient pad is preferably mounted in such manner that it may be rotated to the several radial positions corresponding to the positions of the several die-carriers, so that it may properly coact with whatever die is in the press.

The dies and die-carriers which support them are preferably rectangular in shape and somewhat elongated, so that several operators may conveniently work together on each die to load it with blanks. The size and shape of the resilient pad should preferably be substantially the same as the dies, and said pad should preferably be mounted within a box-like structure, the side walls of which may function to restrict the outward flow of the resilient material of the pad under pressure, for, unless such outward flow is substantially restricted, the pressing effect of the pad in coaction with the dies would be unsatisfactory in many, if not all, instances. Thus arises the necessity of rotating the resilient pad from time to time in order that its position may coincide with the position of the die with which it is next to perform a pressing operation.

The several die-carriers may be moved into and out of the press by suitable motors, such, for example, as electric motors, the controlling circuits of which are preferably so interrelated that only one die-carrier may be moved into the press at a time. The resilient pad, likewise, may be rotated by a motor, such as an electric motor, the circuit of which may be adapted to cause said motor to turn said resilient pad either to the right or to the left to a sufficient extent to bring the pad into mating relationship with a substitute die after one die has been moved out of the press.

The objects, advantages and results, hereinbefore briefly summarized, may be achieved in a structure as described hereinafter in this specification and illustrated in the accompanying drawings, it being understood, however, that this description and the said drawings are employed only for illustrative purposes and should not be taken

as an indication that the invention is to be limited to this disclosure.

The embodiment of the invention disclosed herein, for illustrative purposes, is shown in the drawings, in which:

Fig. 1 is a perspective view of a hydraulic press embodying the principles of the invention.

Fig. 2 is a plan view of the bed of the press showing three of a plurality of die-carriers. The remaining die-carriers are similar to those shown but are omitted to permit suitable enlargement in order to show details more clearly.

Fig. 3 is a horizontal section looking upward on the line 3—3 of Fig. 1, showing the mounting of a holder for a resilient pad pressing member and showing also certain means affecting the rotation of said pad-holder.

Fig. 4 is a vertical side elevation of the main press slide, being broken away to a considerable extent to show in vertical section a pad-holder, a turntable or dial upon which it is mounted, means by which the turntable is rotatably mounted upon said slide, and also a motor for rotating said turntable.

Fig. 5 is a vertical sectional view of yieldable die-carrier supports which may be provided in the bed of the press.

Fig. 6 is a side elevation of a die-carrier and its support, and a motor for operating said die-carrier.

Fig. 7 is an end elevation of a die-carrier as viewed from the right of Fig. 6, partly broken away to show the arrangement of rollers upon which said die-carrier moves.

Fig. 8 is a vertical, transverse section on the irregular line 8—8 of Fig. 6.

Fig. 9 is a detail view, in vertical section, of a die-carrier supporting roller.

Figs. 10a and 10b are explanatory diagrams of certain electric symbols employed in the wiring diagram shown in Figs. 11a, 11b, 11c and 11d.

Fig. 11a is a first portion of an electric wiring diagram adapted for operating and controlling the press illustrated and described herein.

Fig. 11b is a second portion of said wiring diagram.

Fig. 11c is a third portion of said wiring diagram.

Fig. 11d is a fourth portion of said wiring diagram.

It will be helpful in gaining an understanding of the present invention to observe that Figs. 11b, 11c and 11d are continuations, respectively, of Figs. 11a, 11b and 11c, and that when so arranged the principal circuits begin and end at substantially directly opposite points in the diagram. Where this could not be arranged, the circuits have been extended, where possible, almost to such opposite points, and then, where necessary, have been carried into other related circuits.

The press shown in the drawings is a hydraulic press having a base 21 and a crown 22 fixedly held together by tie-rods 23 in a well understood manner. A main press slide 24 may be secured by bolts 25 to the lower end of a ram 26, as best seen in Fig. 4, and may be arranged to slide vertically upon the tie-rods 23, suitable bores being provided in said slide to accommodate said tie-rods, and suitable bushings 27 being provided within said bores and extending about said tie-rods.

As is well understood in the art relating to hydraulic presses, the ram 26 is adapted to receive hydraulic pressure at its upper end to move it and

the slide 24 downwardly to perform a pressing operation. The return or upstroke of the slide 24 may be accomplished through the medium of pistons 28 adapted to be pushed upwardly by hydraulic pressure applied at their lower ends, which upward movement is transmitted through cross-head 29 to pull-back rods 30, and thence to the main slide 24 into which said pull-back rods are screwed or otherwise fixedly secured. It will be observed that the pull-back rods may pass through suitable bores in the crown 22, as illustrated, and may be secured at their upper ends to the cross-heads 29 by nuts 31.

The press illustrated in the drawings is a six-sided press. A flat, horizontal bed 32 is provided upon the base 21, and six die-carrier runways 33 are radially arranged about the said bed and at about substantially the same level as the latter at points between the several tie-rods 23. Said runways may be suitably mounted upon legs or supports 34 which may rest upon the floor adjacent the press. Upon each of the runways 33 is disposed a die-carrier 35, adapted to be moved from the outermost or inoperative position shown in Fig. 1, to an operative position wherein its center is substantially in vertical alignment with the center of the bed 32. In the last-mentioned position a die (not shown), supported on the die-carrier, will be in a position to coact with a pressing member carried on the underside of the slide 24 when the latter is moved downwardly.

It should be understood that one or more operators may tend each of the die-carriers, the number assigned to each carrier being governed chiefly by the nature and number of blanks to be pressed by the die on that carrier in each pressing operation. The radial arrangement of the die-carriers affords areas therebetween wherein the operators and tables for blanks may be positioned.

The die-carriers 35 are all alike and function alike. Each has a flat top 36 having suitable provisions (not shown) for mounting a die thereon. The top 36 is preferably substantially rectangular in shape, as best seen in Fig. 2, and the die or dies (sometimes referred to hereinafter as a "die assembly") used on a carrier would be arranged within the rectangular area of the die-carrier top. The die-carrier 35 is preferably movable longitudinally upon a plurality of wheels 37 suitably mounted on opposite sides of the die-carrier, as best seen in Figs. 6, 7, 8 and 9, through the medium of ball bearings 38 disposed upon stub bolts 39 which may be screwed into or otherwise held within lugs 40 formed on the underside of the die-carrier. In the embodiment illustrated, six wheels are provided on each die-carrier, three on each side, and these wheels roll upon a horizontal portion 41 of angular tracks 42. Vertical side rails 43 of said tracks extend upwardly beyond the wheels 37, where they serve as guides which may coact with adjacent sides of the die-carrier to assure proper linear movement of the latter.

The bottom of each die-carrier is substantially flat and, as best seen in Figs. 7 and 8, is in a horizontal plane slightly above the bottoms of the wheels 37. In order that substantially the entire bottom of the die-carrier may rest upon and be supported by the bed 32 during a pressing operation, yieldable plugs 44 are provided at suitable points in the bed of the press. These plugs are so disposed that when any one of the die-carriers 35 is moved into operative position upon the bed of the press, all the wheels of said die-carrier will rest upon certain of the plugs 44 arranged to co-

act with that die-carrier. For example, referring to Fig. 2, the wheels 37a, 37b, 37c, 37d, 37e and 37f will, when their related die-carrier is in operative position in the press, rest, respectively, upon plugs 44a, 44b, 44c, 44d, 44e and 44f; and, when any other die-carrier is moved into operative position, a similar combination, including different plugs, will coact with the wheels 37 on such other carrier and support the latter.

One form of yieldable plug which may be employed for this purpose is illustrated in detail in Fig. 5. In this particular structure a bore 45, of suitable depth, is provided in the bed 32, and within the said bore may be disposed one or more helical compression springs 46 of such characteristics that a carrier 35 with die and blanks disposed thereon may be supported without yielding. The springs 46 rest upon the bottom of the bore 45 and press upwardly upon a cap 47 having a depending, vertical, annular flange 48 terminating at its lower end in a horizontal annular flange 49 which may be engaged by a shoulder 50 of a suitable keeper 51, in the form of an annular ring, which may be screwed into the bore 45 or otherwise retained therewithin in any suitable manner. It will be seen that by means of this arrangement the wheels 37 of the die-carriers are free to roll upon the plugs 44, but, when pressure is applied to the die on said carrier during a pressing operation, the plugs 44 will yield and permit the flat bottom of the die-carrier to rest upon and be amply supported by the bed 32 of the press.

Each of the die-carriers is provided with similar means for moving it into and out of the press between operative and inoperative positions. These means may be best understood by reference to Figs. 6, 7 and 8, from which it will be seen that each die-carrier is provided on the underside thereof with a longitudinally extending rack 52 suitably fixed to the carrier by machine bolts 53. The rack 52 is driven through the medium of a pinion 54 which is turned, through suitable reduction gearing, by a reversible electric motor 55, mounted upon a support 56 suitably secured to a lug 57 on one of the legs 34 by one or more bolts 58, and to a projection 59 on the base 21 of the press by a bolt 60 which passes through a suitable hole in a lug 61 on the support 56 and is screwed into said projection; all as best seen in Fig. 6.

The motor 55 may, if desired in actual practice, be adapted to operate at several speeds in each direction, but, as such arrangement forms no essential part of the present invention, the motor as described may be considered as a single-speed, reversible motor.

Means are preferably provided, independently of the characteristics of the motor, whereby the die-carrier may start and stop at relatively low speed and may be caused to stop at a precise desired point. The results, just referred to, may be accomplished by the use of a mechanical movement which is immediately hereinafter described.

Members 62 and 63, shaped somewhat like beaver tails, and hereinafter referred to by that name, are fixed at the inner and outer ends, respectively, of the rack 52; the beaver tail 62 being adapted to control the starting and stopping, respectively, of the die-carrier in its movement from and to its outermost or inoperative position; while the beaver tail 63 is adapted to control the stopping and starting, respectively, of the die-carrier in its movement into and from its innermost or operative position.

As shown in Fig. 6, the die-carrier 35 is in its outermost position, and a pair of rollers 64, carried at the outer ends of an arm 65 suitably arranged to rotate with the pinion 54, are in rolling engagement with opposite outer points of the beaver tail 62 in a horizontal line substantially coincident with the center of said pinion. The teeth 52a of the rack 52 are cut away, as best seen at 52b, at the portion thereof which is overlaid by or coincident with the beaver tail 62, so that, when the motor 55 is started to initiate the movement of the die-carrier 35 toward the left, the pinion 54 and, with the latter, the arm 65 and the rollers 64 carried thereby start rotating in a counter-clockwise direction. There being no teeth of the rack 52 in mesh with the teeth of the pinion 54 at that time, movement may be imparted to the die-carrier 35 only through the coaction of the right-hand roller 64, as it arcs upwardly to the left with the rotation of the pinion 54, and the right side of the beaver tail 62.

The beaver tail is so shaped above and below its central horizontal diameter, coinciding with the center of the pinion 54, that the said coaction between the rollers 64 and the side edges of the beaver tail 62 causes the die-carrier to move relatively slowly at first and to increase its speed somewhat as the rack 52 moves to a point beyond where the teeth 52a are cut away and where the said teeth then engage the pinion 54. The progressive increase in speed of the die-carrier, resulting from the said coaction of the rollers 64 and the beaver tail 62, preferably is such that the die-carrier speed, at the moment the said coaction ceases, is substantially the same as the speed at which it will be driven as a result of the direct coaction between the teeth of the pinion 54 and the teeth of the rack 52.

As the die-carrier approaches its innermost position and reaches a point where the teeth of the rack 52, coincident with the beaver tail 63, are cut away, the rollers 64, as they rotate with the arm 65, engage the beaver tail 63 and slow down and stop the die-carrier by a coaction which functions oppositely to that just described with respect to the starting movement of the die-carrier. As the rollers 64 first enter into coaction with the beaver tail 63, one of said rollers engages the beaver tail substantially at its lowermost point and, in its counter-clockwise movement, rolls upwardly to the right along the lower right side of the beaver tail, the other roller 64 meanwhile coacting with an upper portion of the left side of said beaver tail until the die-carrier 35 comes to rest, at which time the arm 65 is in a substantially horizontal position.

It should be observed that the beaver tails 62 and 63 function similarly and that their coaction with the rollers 64 is reversed when the movement of the die-carrier is reversed to bring the latter again to its outermost position. It should also be understood, and it will hereinafter be explained in greater detail, that suitable means are provided for breaking the electric circuit to the motor 55 at the proper time in order to cause the die-carrier 35 to stop at the desired point.

The beaver tail arrangement is useful not only for imparting relatively slow movement to the die-carrier in starting and stopping, but also for assuring that the die-carrier will stop at the precise point desired, both in its innermost and its outermost positions. The latter desirable result flows from the fact that, during a limited portion of the rotation of the arm 65 when the latter is in or nearly in a horizontal position upon the

starting and stopping of the motor, the rollers 64 coact with opposite surfaces of material circumferential length, on the beaver tail, which surfaces are substantially concentric with respect to a point on the beaver tail which coincides with the axis of the pinion 54. During movement of the rollers 64 over such opposite concentric surfaces on the beaver tail, there can be no resulting movement of the die-carrier; hence, to assure stopping of the latter at a precise desired point, it is only necessary to so arrange the circuit cutoff of the motor 55 that the coasting of the latter causes the rollers 64 to move into engagement with said concentric surfaces and to stop while in such engagement. Such a motor cutoff arrangement, of course, may be easily provided.

In order that the beaver tails 62 and 63 may be in positions wherein they may coact with the rollers 64 when the die-carrier is at the precise operative and inoperative positions desired, the said beaver tails are mounted on extensions 66 and 67 at each end of the die-carrier 35, as best seen in Fig. 2. Also, as may be observed from Figs. 6, 7 and 8, the beaver tails extend substantially below the bottom of the die-carrier. This disposition of the beaver tails enables them to be used not only in controlling the starting and stopping of the die-carriers in the manner already explained, but also in guiding a die-carrier as it moves to and from its operative position upon the bed 32 and while it remains in position thereon.

The guiding function, just referred to, is realized by providing radial slots 68 in the top of the bed 32 in alignment with said beaver tails. These slots extend completely across the said bed, and, as the beaver tails on oppositely disposed die-carriers are in a common line extending through the center of said bed, it will be seen that each slot may receive and coact with the beaver tails on either of two opposite die-carriers. The vertical side rails 43 on the die-carrier runways may, of course, only coact with the die-carrier as guides for the latter while the die-carrier is substantially over said runways. The beaver tails perform an important function in guiding the die-carriers at a time when the die-carriers are substantially clear of the vertical side rails 43 of said runways.

A further advantage is derived from using the described beaver tail construction on the die-carriers, inasmuch as the cutaway portion of the teeth 52a, at 52b affords ample clearance between the top of the pinion 54 and the adjacent surface of the rack 52 to accommodate the vertical movement of said rack which occurs when the die-carrier is pushed downwardly somewhat upon the yieldable plugs 44 at the time the press closes.

In the embodiment illustrated in the drawings, a resilient pressing member is mounted on the underside of the slide 24 and is adapted to coact, in the pressing operation, with a die or dies mounted on any one of the several die-carriers which may be moved into operative position upon the bed of the press. In order that such a pressing member may coact properly with any one of said dies, the mounting of said pressing member is such that it may be rotated about a vertical axis passing through the center of the bed 32.

Such a pressing member, in the form of a resilient pad 69 (Figs. 3 and 4) which may be formed of relatively soft rubber or other suitable resilient material, is preferably mounted within a pad-holder 70 in the form of an inverted rec-

tangular shaped box. The inner horizontal dimensions of the said pad-holder are preferably slightly greater than the corresponding dimensions of the die-carrier and die to be used in the press, so that during the pressing operation the die-carrier may extend partly into the pad-holder and compress the material being processed between the die and the pad. The pad-holder 10 may be provided with mounting flanges 11, and with strengthening webs 12, and may be secured in any suitable manner, as, for example, by bolts 13 in a central position upon the under-side of a rotatable, horizontally disposed dial 14.

A spindle 15 formed integrally with the dial 14, or otherwise fixedly secured thereto, extends upwardly from the center of said dial through a bushing 16 fixed within a bore 17 in the slide 24 and into a suitably dimensioned recess 18 in the lower end of the ram 26. A ball bearing assembly 19 is arranged to receive the thrust of a thrust plate 20 which is suitably secured upon the upper end of the spindle 15, as by a screw 21. By this arrangement the dial is effectively supported and may turn freely upon the ball bearing assembly 19.

The dial 14 may be rotated in either direction by a reversible electric motor 22 fixed upon the side of the main slide 24. The said motor drives a pinion 23, preferably through reduction gearing (not shown), which may be carried within the motor casing, and the said pinion may mesh with teeth 24 formed in the periphery of the dial 14 or with similar teeth of a ring gear which may be fixed in any suitable manner upon the periphery of said dial.

As best seen in Fig. 3, a plurality of beaver tails 25 are bolted to and extend outwardly from the dial 14 at desired points thereabout to contact with rollers 26, arranged to turn with the pinion 23 similarly to the coaction of the roller and beaver tail arrangement provided on the die-carriers 35. The beaver tails 25 function similarly to the beaver tails 27 and 28 to control somewhat the speed of the dial in starting and stopping, and to assure stopping of the dial at a precise point desired. It is to be observed that the several beaver tails 25 are so positioned that one of them may coact with the rollers 26 at any one of the six stopping points of the dial.

The press is equipped with various electric switches which control the operation of the moving parts of the press and with suitable dogs for actuating various electric switches. As is well known to those skilled in the design, construction and operation of presses, such dogs and the switches with which they coact may be mounted optionally in various positions, and, as the functioning of said dogs and switches relates primarily to the electric control system of the press, they have not been shown in any of the figures hereinbefore described in detail but are shown diagrammatically in Figs. 11a, 11b, 11c and 11d, which illustrate the said electric control system.

Having an understanding of the press structure as thus far described, its operation may best be understood from Figs. 11a, 11b, 11c and 11d, which, when arranged underneath each other, in the order named, with their long sides in juxtaposition, constitute an electric diagram of the various pieces of electrical apparatus which actuate or cause operation of the various parts of the press. The said diagram includes representations of the various moving parts of the press (proportions being ignored), and illustrates the manner in which certain dog-actuated con-

tact switches control various relays which, in turn, control motors actuating certain moving parts of the press and electric solenoids which, through a suitable valve arrangement, control the closing and opening of the press.

In the said electric diagram, straight lines are employed to indicate wiring connections between the various pieces of apparatus. The said lines necessarily cross in many places but such crossing should be taken as representing connections of wires only where clearly indicated by the use of solid black circular spots at such crossing points.

Referring generally to the several said relays, the latter, structurally, each comprise an electromagnet and various contactors constituting switches which are opened or closed when said magnet is energized and de-energized. Fig. 10a shows symbolically such a relay comprising a magnet 217 and five contactors 217b, 217c, 217d, 217e and 217f, in positions underneath said magnet from which (assuming said contactors to be linked together to move in unison) they may be moved upwardly toward the said magnet, when the latter is energized, so that contactors 217b and 217e move from contacting or closed positions to non-contacting or open positions while contactors 217c, 217d and 217f move from open to closed positions. Hereinafter the several contactors in the several relays will be referred to as switches, and said switches may be referred to as normally open or normally closed, depending upon their positions when their actuating magnet is in de-energized condition.

The use, in the electric diagram, of a symbolic representation such as is illustrated in Fig. 10a, would immeasurably complicate said diagram, and, therefore, symbols as shown in Fig. 10b are employed in said diagram in place of symbols as shown in Fig. 10a. In the electric diagram a relay magnet and its associated contactors or switches are not shown in their actual structural relationship, but such relationship is accurately and clearly indicated in said diagram by applying to the several contactors or switches a reference character formed by adding a distinguishing letter, taken from the first part of the alphabet, to the number used as a reference character for the magnet which actuates such contactors or switches, irrespective of where said switches may be located in said diagram. Thus, Fig. 10b symbolizes magnet 217 in de-energized condition with switches 217b and 217e in normally closed positions and switches 217c, 217d and 217f in normally open positions. Throughout the drawings all relays are represented by the symbols shown in Fig. 10b, and the magnetically controlled switches which are normally closed may be distinguished by the diagonal line extending through the representation of contact points, while the absence of such a diagonal line indicates a magnetically controlled switch as being normally open. For an example of this use of symbols see magnet 201 in Fig. 11b, normally open switches 201a, 201b and 201c, also in Fig. 11b, and normally open switch 201d in Fig. 11c, all said switches in an actual structure being associated with and operated by said magnet 201. It is understood, of course, that the several magnets and the switches controlled thereby are ordinarily mounted in practice upon a suitable panel usually disposed near the press.

In Fig. 11a, in order to simplify the electric diagram, only three of the six movable die-

carriers are diagrammatically illustrated, such structure being shown in broken lines in order to cause the electric apparatus and wiring to stand out clearly. It should be understood that the three omitted die-carriers have similar associated electric apparatus and are operated and controlled similarly to those shown.

The several die-carriers 35 are distinguished from each other in Fig. 11a as A, B and C, and in Fig. 11c the same letters are employed within circles to indicate corresponding positions of the rotatable dial. In the latter figure positions D, E and F of said dial are similarly indicated, corresponding to the positions of the three die-carriers omitted from the diagram. In the various diagrams in Figs. 11a and 11c the several die-carriers 35 and the rotatable dial 74 are to be considered as viewed from above.

Referring to Fig. 11a the die-carrier A has a dog A1 mounted thereon on one side thereof and two dogs A2 and A3 on the other side. All these dogs may be mounted toward the outer end of said carrier by any suitable means, such as, for example, by a rigid extension 106. Adjacent to one side of the die-carrier and in positions wherein they may be actuated by the dog A1 are arranged dog-actuated switches A11 and A12, which are preferably fixedly mounted by any suitable means upon some non-movable portion of the press structure, the former switch being disposed toward the outer end of the die-carrier support and the latter switch toward the inner end of said support. Somewhat similarly arranged adjacent to the opposite side of the die-carrier, in positions wherein they may be actuated by the dogs A2 and A3, are dog-actuated switches A21, A22, A32 and A42, which also are preferably fixedly mounted by any suitable means upon non-movable portions of the press structure. Switch A21 is disposed toward the outer end of the die-carrier support, and switches A22, A32 and A42 are disposed toward the inner end of said support.

The several dog-actuated switches referred to in this specification may preferably be swing-arm type switches which operate when said arm is engaged and swung angularly by a coacting dog. The "normal" conditions of such switches (the conditions thereof when not engaged by any coacting dog) are indicated by legends on the electric diagram.

The dogs A2 and A3 are preferably so disposed that they move in different paths with the movement of the die-carrier. In the present disclosure it should be considered that they are disposed at different levels and that dog A3 protrudes sidewise with respect to the die-carrier, somewhat more than dog A2. It also should be understood that, in the present disclosure, switches A32 and A42 are disposed with their swing-arms in the path of dog A2, and, hence, are operated by said dog A2, and that switches A21 and A22 are disposed with their swing-arms in the path of dog A3 and, hence, are operated by said dog A3. The switch-engaging surfaces of dogs A1 and A3 may be quite long, as indicated in the drawings, but dog A2 should preferably have only a relatively short surface, as illustrated, adapted to operate its associated switches, this being desirable because switch A32 should only be momentarily operated and switch A42 should be held closed only when the die-carrier is in the precise "in" position in which it will coact properly with the pad 69 in a pressing operation, all as hereinafter more fully explained.

Also, for reasons hereinafter more fully explained, the switch A32 should be of the type which operates to close only when swung inwardly, with the "in" movement of the die-carrier.

It will be perceived that, under the arrangement just described, when the die-carrier is in its outermost position, dog A1 holds switch A11 open and dog A3 holds switch A21 closed, and when said die-carrier is in its innermost position dog A1 holds switch A12 open and dogs A2 and A3, respectively, hold switches A42 and A22 closed. It will also be helpful to observe that, as the die-carrier approaches "in" position, dog A2 engages and momentarily closes switch A32. Said dog, however, passes beyond and disengages switch A32, permitting it to open, before the die-carrier comes to rest at its innermost position. It should be understood that all die-carriers on the press are provided with coacting dogs and switches which are similar to and function as those described in this paragraph. They have been given reference characters comprising the same numerals as those here referred to, pre-fixed, however, by the letters used to identify the related die-carriers, thus, dogs B1, C1, etc., and switches B11, C11, etc.

Referring to the larger showing of the rotatable dial 74 toward the left of Fig. 11c, four similar dogs w, x, y, z are suitably formed or otherwise carried, in a common horizontal plane, about the periphery of and on said dial. The said dogs are disposed 90° apart and are adapted to coact with and operate switches AL and AR, BL and BR, CL and CR, DL and DR, EL and ER, and FL and FR, in a manner hereinafter explained, whereby to control the rotation of said dial so that the said dial and the pad-holder 70, carried thereby, may turn, if necessary, either to the right or left, as indicated by the directional arrow, to cause the pad-holder to mate with a selected die carried on any die-holder. The last-mentioned switches are fixedly mounted, by any suitable means, upon the slide 24 of the press, in such positions that they may coact with and be operated by the several dogs w, x, y and z.

Also, in Fig. 11c, two other horizontal planes are presented with reference to the dial 74. In the upper one of these presentations are shown six similar dogs 107, suitably formed or otherwise carried in a common horizontal plane different from the plane of the dogs w, x, y and z, about the periphery of and on the dial 74. The dogs 107 are disposed 60° apart and are adapted to coact with and operate switch SL, in a manner hereinafter explained, whereby to stop left movement of the dial 74 as indicated by the directional arrow thereon. In the lower one of these presentations are shown six similar dogs 108, suitably formed or otherwise carried, in a common horizontal plane different from the planes of the dogs w, x, y and z and dogs 107, about the periphery of and on the dial 74. The dogs 108 are disposed 60° apart and are adapted to coact with and operate switch SR, in a manner hereinafter explained, whereby to stop right movement of the dial 74 as indicated by the directional arrow thereon. The switches SL and SR are fixedly mounted, by any suitable means, upon the slide 24 of the press, in such positions that they may coact with and be operated by the dogs 107 and 108 respectively. Also, in the lower one of these presentations is shown a dog-actuated switch DS, so positioned on the press slide 24 that it is engaged and held closed by one of

the dogs 108 when the dial 74 is at rest in any one of the six positions in which the pad-hoist 70 may function in a pressing operation. Said switch DS is adapted to function, in a manner hereinafter explained, to assure that the press may not close except when the dial 74 is in a proper pressing position.

It should be observed that the several dogs 107 are not disposed directly over the dogs 108. Taking as a stopping point, the common circumferential point indicated on the two small diagrammatic presentations of the dial 74 by the arrows 109, it will be apparent that, whenever the dial stops rotating, the dog 107 nearest said point will be somewhat to the left thereof, while the nearest dog 108 will be somewhat to the right thereof. The circumferential disposition of the dogs 107 is preferably such that, when the dial 74 is rotated to the left, the first dog 107 to engage switch SL momentarily closes the latter and stops rotation of said dial as hereinafter explained. After such operation of said switch SL, the coasting of dial motor 82 carries the said dog somewhat beyond said switch as indicated in said presentation in Fig. 11c. Dogs 108 are so circumferentially disposed as to function similarly to dogs 107 to stop right rotation of the dial. Each of switches SL and SR should be of the type which operate when the swing-arm thereof is swung in one direction but not in the other direction, and be so disposed that on left rotation the switch SR is inoperative even though tripped, and on right rotation switch SL is similarly inoperative.

Although the dogs *w*, *x*, *y*, *z*, 107 and 108 have been described herein as disposed in different horizontal planes, it will be understood that other arrangements thereof may be employed to yield the desired operation of the press.

Switches SU and SD, which, as hereinafter explained, respectively function to stop up and down movement of the press slide 24, are suitably fixed, the former upon the crown 22 of the press and the latter upon the base 21 of the press. The said switches, respectively, are operated by dogs 110 and 111 fixed upon a rod 112 which is suitably connected, as by an arm 113, to the slide 24, and adapted to move vertically with said slide within guides 114 and 115 suitably connected to the crown 22 and the base 21 of the press.

The relation of the electric apparatus to the press, whereby opening and closing of the latter is accomplished, is shown in Fig. 11d. As illustrated therein, a hydraulic chamber 89, adapted to effect the closing stroke of the press, is suitably connected by a pipe line 90 to one chamber in a distributing valve 91, and hydraulic chambers 92, adapted to effect the opening of the press, are connected by a pipe line 93 to another chamber in said valve. A fluid pump 94, which may be driven by an electric motor (not shown), draws fluid from a fluid reservoir 95 through a pipe line 96 and pumps it through a pipe line 97 to a third chamber in the distributing valve, while a fourth and a fifth chamber in said valve are connected by a pipe line 98 to the said reservoir.

The several chambers of the distributing valve and the inner construction thereof are substantially as shown in the drawing. The operation of said valve is such that when plunger 99 of said valve is in its uppermost position, as shown in the diagram, the several pistons 99a, 99b and 99c, formed integrally with said plunger, will cause fluid, pumped into the valve through pipe 97, to

be discharged from said valve through pipe line 93 into hydraulic chambers 92 to open the press, the fluid from chamber 89 meanwhile being exhausted through pipe line 90 into the distributing valve 91 and thence through pipe line 98 into the fluid reservoir 95. When the plunger 99 is moved downwardly to a lowermost position, the pistons 99a, 99b and 99c will cause fluid, pumped into the valve through pipe 97, to be discharged from said valve through pipe line 90 into hydraulic chamber 89, causing the press to close, the chambers 92 meanwhile being exhausted through pipe 93 into the distributing valve 91, and thence through pipe line 98 into the fluid reservoir.

The movement of the plunger 99 to the several positions just referred to may be controlled by electric solenoids 100 and 101, through the medium of a lever 102 which is pivoted at an intermediate point upon a bracket 103 suitably fastened to the casing of the distributing valve. The opposite ends of the lever 102 are connected to the two solenoids by links 104 and to an upper-end extension of the plunger 99 by a link 105. When solenoid 101 is energized, the right end of the lever 102 is drawn downwardly and the plunger 99 is moved to its uppermost position, thereby causing the press to open in the manner already explained. On the other hand, if solenoid 100 is energized, the right end of the lever 102 is drawn upwardly, thus moving plunger 99 to its lowermost position, thereby causing the press to close.

When neither of said solenoids is energized, the plunger 99 is moved to and held in an intermediate position by a spring (not shown) located at the lower end of said plunger within the casing of the valve 91, in which position the pistons 99a, 99b and 99c are so disposed within said valve that fluid cannot move through either pipe line 90 or line 93. Thus, when neither solenoid is energized, the press slide 24 is held immovable. In order to handle the fluid discharged from the pump 94 while the plunger 99 is in said intermediate position, interconnected longitudinal duct 99d in said plunger and lateral ducts 99e in the pistons 99a, 99b and 99c are provided to pass fluid, from pipe 97, through the interior of said plunger and pistons, into pipe 98 and thence into reservoir 95. The two solenoids just referred to are electrically controlled, in a manner to be hereinafter explained, to automatically open and close the press.

Considering now Figs. 11a to 11d, inclusive, together, main power wires 301 and 302 are connected in parallel to a suitable source of electric energy. Each circuit includes only one relay magnet. The magnets have been given reference numbers in a 200 series, such, for example, as 201, 219, etc., and all the wires which function only in one circuit are given reference numbers of the magnet in that circuit with a letter suffix from the latter part of the alphabet; thus, the wires in circuit with magnet 201 have been numbered 201l, 201m, etc.; the wires in circuit with magnet 219 have been numbered 219l, 219m, etc. Other wires, common to several circuits, have been given reference numbers in a 300 series.

The wire 301 is connected to a main take-off wire 303 through a series of six, manually operable, normally closed safety switches 304a, 304b, 304c, 304d, 304e and 304f (Fig. 11a). One of said safety switches is provided for and mounted conveniently near to each die-carrier, so that at any time, as in an emergency, an operator of any one

of said die-carriers may readily open one of said safety switches and stop the press. These safety switches, and selector push-button switches 305, 307, etc., hereinafter referred to, are the only parts of the disclosed electric apparatus which the operators of the press must manipulate. Most of the circuits are considered as proceeding from main take-off wire 303 or from other so-called take-off wires, hereinafter mentioned, to wire 302, and, as far as possible, the various circuits have been arranged to begin and end at said wires at substantially similar levels on the diagram.

A cycle of operation may be considered as starting with all the apparatus in the positions shown in Figs. 11a, 11b, 11c and 11d, except that both solenoids 100 and 101 should be considered as de-energized and plunger 99 of valve 91 in its intermediate position, holding the press slide 24 in the "up" position indicated.

Assume that operator B (each operator being herein identified by reference to the letter characterizing the die-carrier which he operates) has finished loading his die with blanks and desires to move it into the press in order to perform the pressing operation on said blanks. He presses selector button switch 306, thereby momentarily closing a pre-selection circuit from main take-off wire 303 to wire 302 through then-closed switch 207b, pre-selection take-off wire 311, wires 313 and 2021, magnet 202, wire 202m, switch B21 (then held closed by dog B2) and wires 202n and 314. This closed pre-selection circuit energizes magnet 202, which thereupon simultaneously operates all switches controlled thereby, i. e., it closes switches 202a, 202b, 202c (Fig. 11b), and 202d (Fig. 11c), all of which are normally open.

Switch 202a, upon being closed by magnet 202 at the beginning of the cycle, holds said pre-selection circuit closed even after button switch 306 is released by operator B by maintaining a connection direct from main take-off wire 303 through wire 202p to wire 2027. Thus, the said pre-selection circuit is maintained until switch B21 is opened by disengaging dog B2 as carrier B moves inwardly in a manner hereinafter explained.

Switch 202b, upon being closed by magnet 202 at the beginning of the cycle, closes a circuit from main take-off wire 303 to wire 302, through wire 207m, magnet 207, and wire 207p. The function of the latter circuit is to open switch 207p, the only switch operated by the magnet 207, thereby preventing the establishment of a pre-selection circuit for any of the other die-carriers until the die-carrier first selected (carrier B in the present example), on moving inwardly, has opened switch B21, thus de-energizing magnet 202, whereby switch 202b is opened and magnet 207 de-energized. This permits switch 207b to close again so that, at any time after one die-carrier has started to move inwardly, the operator of any other die-carrier may press the button switch controlling his carrier to assure that it will be the next one to enter the press.

Switch 202d (Fig. 11c), upon being closed by magnet 202 at the beginning of the cycle, coacts with switch BL to assure that dial 74 and pad-holder 70 on said dial will turn 60° to the left so that said pad-holder will move from the position thereof indicated in solid lines (its disposition at the beginning of the cycle) to the vertically indicated position in which said pad-holder will mate with die on carrier B after the latter has moved into the press.

The further operation of the dial 74 will be 75

ignored in the remaining description of the operation of the several die-carriers, but will be fully explained hereinafter, following said die-carrier description.

Switch 202c, upon being closed by magnet 202 at the beginning of the cycle, closes a selection-maintaining circuit from main take-off wire 303 to wire 302, through switch 217e, selection-maintaining take-off wire 315, wires 317 and 212z, magnet 212, wire 212n, switch 211c, wire 318, switch 213c, wire 320, switch 218b, wire 321, and thence through switches 212b and 212c, all the switches in said circuit then being in closed position in response to the then existing conditions of their respective controlling magnets. The circuit through magnet 212, just described, energizes the latter and, hence, at the beginning of a cycle, operates switches 212a, 212b, 212c and 212d, all of which are controlled by magnet 212. The effect of the operation of the last-mentioned switches will now be described.

Switch 212a, upon being operated by magnet 212 when the latter is energized at the beginning of the cycle, closes to hold the circuit through magnet 212 closed by maintaining a connection direct from main take-off wire 303 through wire 212m to wire 212l. Thus, the said circuit is maintained through magnet 212, and, consequently, the selection of die-carrier B, as the next one to go into the press, is maintained until the arrival of the said die-carrier at "in" position, when switch 218b is opened by the energizing of magnet 218, which takes place when switch B32 is tripped closed by dog B2.

Switches 212c and 212d, upon being operated by magnet 212, when the latter is energized at the beginning of the cycle, open whereby to assure that, while the circuit through magnet 212 is functioning, the circuits through magnets 211 and 213, in which circuits said switches are located, will not function, thus assuring that no selection may then be maintained through the medium of magnets 211 and 213 for die-carriers A and C which the two latter magnets control. 45 While, as already explained, a further pre-selection of another die-carrier to go into the press may be established in any of magnets 201, 202, 203, etc., immediately after one die-carrier (carrier B in the present explanation) has started to move into the press, such pre-selection may not be carried into any of the selection-maintaining magnets 211, 212, 213, etc., while die-carrier B (or any other carrier) is in other than its "out" position, for, during all of the latter period, switch 217e is held open by magnet 217, which is energized during said period because switch B11 is closed while carrier B is in other than "out" position. Thus, double assurance is provided that only one die-carrier selection may become effective at one time.

Switch 212b, upon being operated by magnet 212 when the latter is energized at the beginning of the cycle, closes whereby to establish a connection from main take-off wire 303 through wire 322 to motor 55 of die-carrier B at a common terminal, on said motor, of both the "in" and "out" windings thereof. The said connection may continue through the "in" winding of said motor, and thence by wire 323, switch 281d and wire 324 to wire 302, whereby to cause said motor to operate and move die-carrier B inwardly. To cause outward movement of the said die-carrier, a similar connection may continue from said common terminal, through the "out"

winding of said motor, and thence by wire 325, switch 232d and wire 326 to wire 302. The manner in which switches 231d and 232d are closed to cause "in" and "out" operation, respectively, of the motor 55 of die-carrier B will be herein-after explained.

It should be understood that while the closing of switch 212b by magnet 212 establishes connection to the said common terminal of the motor of carrier B, the corresponding switches 211b and 213b, which are similarly related to carriers A and C, respectively, and similar switches (not shown), related to the three omitted carriers, all remain open, thus assuring that only the motor of carrier B will operate. Also, having a circuit partially established through the motor of carrier B, it is evident that said motor circuit will be completed through the "in" winding thereof to cause carrier B to move inwardly if switch 231d is closed, and will be completed through the "out" winding thereof to cause said carrier to move outwardly if switch 232d is closed. Various dog-actuated switches operated by dogs carried by the carrier (carrier B in the cycle being described) control the circuits through magnets 217 and 220, to operate switches which function to control the circuit through "in" magnet 231 and "out" magnet 232, and, hence, to control the said switches 231d and 232d operated, respectively, by the two latter magnets, whereby the carrier may move "in" when it is out and may move "out" when it is in.

As it is desired to cause die-carrier B to move from its "out" position into the press, the inter-relationship and coaction of magnets 217, 220, 231 and 232 and the switches operated thereby may best be considered by first observing the condition of such electric apparatus when all die-carriers are "out."

When the said carriers are all "out," magnet 220 is energized by reason of the fact that switches A12, B12, C12, and 219b, which are arranged in series and control the circuit through said magnet, are all in closed position, and magnet 217 is de-energized by reason of the fact that the switches A11, B11 and C11, which are all connected in parallel relatively to each other and are collectively connected in series in the circuit through magnet 217, are all held open by the dogs A1, B1 and C1.

Following the effect of the conditions stated in the preceding paragraph, into the circuit of magnet 231, it will be seen that, when all die-carriers are "out," said magnet is in a closed circuit between main take-off wire 303 and wire 302 which includes switch 217b, then in its normally closed position because of magnet 217 being de-energized, switch 232b, then in its normally closed position because of magnet 232 being de-energized as herein-after explained, and wires 231b and 327. Hence, "in" magnet 231 is energized and, in consequence, switch 231d is closed, completing a circuit through the "in" winding of the motor of die-carrier B, causing the latter to move inwardly, as is desired. Meanwhile, magnets 220 and 231 being energized as aforesaid, switches 220b and 231b are held open, thus keeping "out" magnet 232 de-energized and keeping switch 232d open, thereby preventing the establishment of a circuit through the "out" winding of the carrier motor at that stage of the cycle.

As carrier B starts to move inwardly, upon closing of the carrier motor circuit in the manner just explained, dog B1 disengages and thus closes switch B11, thereby energizing magnet 217

and, in consequence, opening switch 217b. This, considered alone, would, of course, open the above-described circuit through magnet 231, but, as it is essential to keep the latter magnetized 5 in order to hold switch 231d closed, whereby to maintain the circuit through the carrier motor until the carrier reaches "in" position, a maintaining circuit was established around said switch 217b while the carrier was out, said circuit including switches 220c and 231a, the former switch being held closed because of magnet 220 being energized at all times except when a carrier is "in," and the latter switch being held closed as long as magnet 231 itself is otherwise maintained 15 in energized condition.

Also, as carrier B starts to move inwardly, the energizing of magnet 217, resulting from the closing of switch B11, causes switch 217e to open, thus preventing any further selection circuits 20 from being established and maintained, either through magnets 211, 212 and 213, controlling the maintenance of die-carrier selection, or through the several dog-actuated switches controlling the direction of movement of the rotatable dial 74, until the selection circuits already 25 established therethrough have fully performed their functions and have been broken.

Also, as carrier B starts to move inwardly, dog B3 disengages and opens switch B21, thereby de-energizing magnet 202. In consequence, switches 30 202a, 202b, 202c and 202d open, magnet 207 is de-energized, and switch 207b closes, whereby to restore the several pre-selection circuits to a condition wherein they may function in the 35 manner already explained when another die-carrier is loaded and ready to be moved into the press. As will be herein-after explained, such further selection may be established as soon as one die-carrier (carrier B in the present cycle) 40 has started to move into the press.

Having pursued the operation of the various electric circuits and apparatus to the stage in the cycle wherein the carrier B, in moving inwardly, has caused dogs B1 and B3 to disengage 45 switches B11 and B21, it is apparent that the carrier B will continue to move inwardly and that there will be no further changes in the various die-carrier circuits until said carrier has moved inwardly sufficiently to cause said dogs 50 and dog B2 to engage and operate switches B12, B22, B32 and B42. The effect of such operation of said switches, as bearing upon the operation of the die-carriers, will now be explained.

Upon carrier B reaching "in" position, dog B1 55 engages and opens switch B12, de-energizing magnet 220, thereby opening switch 220c and thus breaking the maintaining circuit through "in" magnet 231, de-energizing the latter. This causes switch 231d to open, thus breaking the 60 circuit through the "in" winding of the motor of carrier B, whereby to stop the "in" movement of the latter. Upon magnets 220 and 231 becoming de-energized, as just explained, switches 220b and 231b close, thereby energizing "out" magnet 232 and, in consequence, closing switch 232d 65 which is connected by wires 325 and 326 between wire 302 and the "out" winding of the motor of carrier B. The said motor, however, will not then operate to cause carrier B to move out immediately, for switch 212b, which also controls the circuit of said motor, has been opened in the manner herein-after described, and will not close again to complete the circuit through said motor 70 and move the die-carrier out until after the

pressing operation has been completed and the press opened.

Similarly to the maintaining circuit which held "in" magnet 231 energized while carrier B moved to its "in" position, a maintaining circuit is established around switch 220b to hold "out" magnet 232 energized until carrier B, later, reaches its "out" position. The latter circuit includes switches 217c and 232a, the former switch being held closed because of magnet 217 being energized when any carrier is in other than an "out" position, as already explained, and the latter switch being held closed as long as magnet 232 itself is otherwise maintained in energized condition.

Upon carrier B reaching "in" position, dog B3 engages and closes switch B22 and as the latter is in series with then-closed switches 219b and C12, said switches form a connection between main take-off wire 303 and the side of magnet 212 which is remote from wire 302. The circuit through magnet 212, however, cannot be re-established at that time, nor thereafter, to close switch 212b in order to start carrier B moving outwardly, until the press has closed and opened again. This is due to the fact that switch 221b is opened immediately upon carrier B reaching "in" position and held open during the closing stroke of the press slide 24, and also because switch 218b, in the circuit of said magnet 212, is opened upon carrier B reaching "in" position and cannot close again until the slide 24 has completed its subsequent opening stroke, all as hereinafter more fully explained.

Upon carrier B approaching "in" position, dog B2 engages and momentarily closes switch B32, completing a circuit between main take-off wire 303 and wire 302, including wires 218r and 218s, switch B32, wires 218s and 218v, magnet 218 and then-closed switches 217d and 224d. Upon magnet 218 becoming energized through this circuit, switch 218b opens, thus de-energizing magnet 212 and opening switches 212a and 212b, the latter of which controls the motor of carrier B. Thus, said motor is stopped and cannot operate again until a circuit is again established through the "out" winding thereof upon the completion of a pressing operation. Although, as just stated, switch B32 is closed only momentarily, that momentary closing and the consequent energizing of magnet 218 causes switch 218a to close and the latter switch replaces switch B32 in holding magnet 218 energized even after dog B2, in completing its "in" movement, has passed beyond and disengaged and opened switch B32.

After dog B2, in the latter part of its "in" movement, disengages switch B32, it engages and closes switch B42, which is connected in series with magnet 221 by wires 328, 329, 330 and 331. Dog B2, as may be observed, has a very small switch-engaging surface, and, hence, switch B42 may not be held closed by said dog unless the die-carrier is in the precise "in" position in which dies carried thereby may properly cooperate with the pad 69 and the pad-holder 70. The disposition of the dog B2 and of the switch B42 should be such that said switch will not be held closed by said dog unless the die-carrier B comes to rest in that position upon the bed of the press in which such proper cooperation may occur. Under this arrangement, the switch B42 will be held closed and magnet 221 may be energized to close the press, in the manner hereinafter described, only if the die-carrier is in the proper position on the bed of the press.

The electric apparatus is such that, immediately upon any carrier reaching "in" position, the slide 24 of the press is automatically caused to move downwardly to perform a pressing operation, and immediately upon said slide reaching a point where such pressing operation is complete, said slide automatically returns to its uppermost or open position and there automatically stops, whereupon the die-carrier that has been in the press is automatically caused to move from an operative position within the press to an inoperative position alongside the press. This automatic operation is largely controlled through magnets 218, 219, 221, 223 and 224 and solenoids 100 and 101, most of which are shown in the diagram in Fig. 11d. As the circuits in the latter figure are so clearly defined in the drawings, it appears unnecessary to refer to the various wires in said circuits by any particular reference characters.

The solenoid 100 is adapted to operate valve 91 in order to cause downward or closing movement of the press, and the circuit through said solenoid is completed through switches 221d and 221e, both of which are operated by magnet 221. Solenoid 101 operates said valve in order to effect upward or opening movement of the press, and its circuit is controlled by switches 223d and 223e, both of which are operated by magnet 223.

It should be helpful, at this point, to observe that magnet 218 and the switches which it operates perform important functions not only in stopping the "in" movement of the die-carrier in the manner already explained, but also in initiating the closing of the press and in initiating the "out" movement of the die-carrier upon the press slide completing its opening stroke.

As hereinbefore stated, magnet 218 is energized upon completion of the "in" movement of carrier B by reason of switch B32 being actuated by dog B2. Upon magnet 218 thus becoming energized, switch 218c in the circuit of magnet 221 is caused to close to initiate closing of the press. Of the other switches in said circuit, switch 220e is in its normally closed position, switch 217f is held closed due to the fact that magnet 217 is energized while any carrier (in this case, carrier B) is in other than "out" position, switches 233c and 234c are in their normally closed positions, switch 224b is held closed by reason of the fact that at that time magnet 224 is in energized condition, and, if the die-carrier and the dial are in their precise pressing positions, switch B42 is held closed by dog B2 and switch DS is held closed by one of the dogs 108. Thus, the closing of switch 218c completes a circuit through magnet 221, energizing the latter, whereupon switches 221d and 221e close, completing a circuit through and energizing the "down" solenoid 100. The said solenoid operates valve 91, causing plunger 99 thereof to move to its lowermost position so that fluid pumped into said valve through pipe 97 may pass from said valve, through pipe 90, into chamber 89, whereby to effect the downstroke of the press.

At this point, it is well to observe that, during the closing and opening of the press, magnet 212 must remain de-energized to prevent the closing of switch 212b, which if it occurred during the said portion of the operating cycle, would cause the die-carrier to start moving outwardly in conflict with the closing and opening of the press. The holding of magnet 212 in its de-energized condition to prevent such conflict is as-

sured through the functioning of switches 221b and 218c in the circuit of that magnet in the manner now to be described.

Upon magnet 221 becoming energized, by the closing of switch 218c, to cause down movement of the press in the manner just described, switch 221b opens, so that while magnet 221 is energized, i. e., during the entire downstroke of the press, there is no possibility of any circuit being established or maintained through magnet 212. Switch 219c remains closed until the down movement of the press slide 24 causes dog 110 to disengage switch SU, mounted on the crown 22 of the press, whereupon the latter switch opens and de-energizes magnet 219, as a result of which switch 219c opens, thus causing a further break in the circuit through magnet 212. Upon the completion of the downstroke of the press, switch 221b closes, but switch 219c remains open and cannot close until the dog 110 re-engages and closes switch SU upon the completion of the opening stroke of the press slide 24. Hence, it is assured that the die-carrier may only move when the press is open. As will be hereinafter explained, said switches 219c and 221b also serve to assure that the dial 14 may only rotate when the press is open.

Although switches 219c and 221b serve to prevent magnet 212 from becoming energized during the closing and opening of the press, nevertheless, in order to avoid possible conflict, at the moment dog B2 closes switch B32, between magnet 212, which at that moment would tend to hold the circuit closed through the carrier motor, thus tending to reverse the carrier and move it outwardly, and magnet 221, which at that moment should become effective to start the down movement of the press slide 24, switch 218b in the circuit of magnet 212 is caused to open by reason of magnet 218 becoming energized immediately upon the closing of the switch B32 by the dog B2. In this way the opening of switch 218b operates to de-energize magnet 212 independently of the action of switch 221b. Thus, it may be said that the circuit through magnet 212 is broken on the carrier reaching "in" position, primarily by the opening of switch 218b, and, secondarily, by the opening of switches 221b and 219c, the latter switch serving to hold magnet 212 de-energized until the press has completed its closing and opening strokes.

Having the foregoing understanding of the manner in which the various dog-actuated switches function upon die-carrier B reaching its "in" position, the further operation of the press may now be considered. When the circuit through magnet 221 is closed by the closing of switch 218c, as already explained, the press slide 24 starts to move downwardly in response to hydraulic pressure established in chamber 89 by reason of the operation of the "down" solenoid 100 and the valve 91, under the control of the said circuit. Thereupon, the dog 110 disengages and opens switch SU, thereby de-energizing magnet 219, in consequence, not only opening switch 219c to hold open the circuit through magnet 212, as just explained, but also opening switch 219b, thereby breaking the connection which extends through switch B22 between the main take-off line 303 and the side 70 of magnet 212 which is remote from wire 302, so that, while the said slide 24 is in any position other than its open position, the circuit through magnet 212 is broken at both ends thereof.

As the press slide 24 reaches either a prede-

termined "down" position or a position wherein the restraint offered by the blank or blanks being pressed has built up sufficient back pressure in chamber 89, the said slide is caused to stop its down movement and automatically start moving upwardly. To accomplish this, there are provided two normally closed switches in series in the circuit of magnet 224. One of these switches, switch SD, is a dog-actuated switch which may be opened by dog 111 if the press slide moves downwardly to the said predetermined "down" position; the other switch, switch PS, is a pressure switch which is hydraulically connected to pipe 90 through pipe 90a, the electric contacts of said switch being connected, of course, in the wiring comprising the circuit through magnet 224. The latter switch may be adjusted so that it will open upon the pressure in chamber 89 rising to a predetermined point, so that the press slide may be caused to reverse its movement and start moving upwardly, in the manner now to be described, even though it does not move downwardly sufficiently to operate switch SD.

Upon the opening of one or the other of switches SD or PS, magnet 224 becomes de-energized, thereby opening switch 224b in the circuit of magnet 221, whereby to de-energize the latter, and closing switch 224c in the circuit of magnet 223 to energize the latter, switch 219d in the latter circuit, at that time, being in its normally closed position, and switch 221c in said latter circuit being closed at the completion of the downstroke of the press slide 24 by the de-energizing of magnet 221.

Upon magnet 221 becoming de-energized and magnet 223 becoming energized in the manner just explained, switches 221d and 221e open, thereby de-energizing the "down" solenoid 100 while switches 223d and 223e close, thereby energizing the "up" solenoid 101. This reversal of the condition of the solenoids 100 and 101 operates to shift the plunger 99 of the valve 91 from its lowermost position to its uppermost position. In the latter position of said valve the fluid entering said valve through pipe 97, instead of being pumped into chamber 89, as was the case during the downstroke of the press, is pumped into push-back chambers 92 through the pipe 93, thus imposing pressure on the lower ends of push-back pistons 28 and thereby causing the press slide 24 to start moving upwardly.

It will be seen that, although magnet 221 becomes de-energized upon the completion of the downstroke of the press slide 24 and thereby closes switch 221b, the circuit through magnet 212 cannot at that time be re-established for the reason that switches 219b and 219c, in the latter circuit, still are open and will remain open until magnet 219 is energized upon the completion of the upstroke of the press slide 24.

The de-energizing of magnet 224 in the manner just explained, upon completion of the downstroke of the press slide 24, causes switch 224d in the circuit of magnet 218 to open, thereby de-energizing said magnet and, in consequence, opening switch 218a in the circuit of said magnet and closing switch 218b in the circuit of magnet 212. After such de-energizing of magnet 218, it may not be again energized until the die-carrier that is in the press has moved outwardly and it, or another die-carrier, has moved into the press in a new cycle similar to that thus far described; this because magnet 218 may only be energized by the closing of switch B32 as carrier B moves inwardly, or when one of the

other carriers moves inwardly and a corresponding switch on such other carrier is similarly closed.

Switch B32 and the corresponding switches associated with the other die-carriers are of the type which operate only when the swing-arm thereof is swung in the one direction, that is, when it is swung inwardly with the "in" movement of a die-carrier. Thus, although switch B32 may be engaged by dog B2 in the outward movement of said die-carrier, nevertheless said switch will not close as a result of such engagement, and hence on the "out" movement of the die-carrier no circuit will be established through magnet 218. It is therefore apparent that switch 218b in the circuit of magnet 212 remains closed during the "up" movement of the press slide, during the outward movement of any die-carrier, and until some die-carrier has moved inwardly and again energized magnet 218 and opened said switch 218b in the manner already described. Notwithstanding the fact that switch 218b is closed during the part of the cycle just referred to, nevertheless it is apparent that magnet 212 may not be energized to close switch 212b, whereby to start die-carrier B moving outwardly, until the press slide 24 completes its upstroke and energizes magnet 219 whereby to close switches 219b and 219c in the manner about to be explained.

As the press slide 24 approaches its uppermost position, dog 110 engages and closes switch SU, thereby energizing magnet 219. One result of magnet 219 becoming energized is the opening of switch 219d in the circuit through magnet 223, which de-energizes the latter and causes switches 223d and 223e to open, thus de-energizing "up" solenoid 101, whereupon, in the manner already explained, plunger 99 moves to its intermediate position, thus stopping all further movement of the press slide 24. Upon magnet 223 becoming de-energized, switch 223b in the circuit of magnet 224 closes, energizing said magnet, whereupon switch 224c in the circuit of magnet 223 opens, thus opening the connections at both ends of the latter magnet, to assure that it may not again be energized and function until the press has again been closed.

Another result of magnet 219 becoming energized, upon completion of the upstroke of the press, is that switches 219b and 219c are caused to close, thereupon completing a circuit through said magnet extending from main take-off wire 303 through switch 219b, wire 220l, switch C12, wire 220m, wire 212r, switch B22 (then closed because of die-carrier B being "in"), wire 212p, magnet 212, wire 212n, switch 211c, wire 319, switch 213c, wire 320, switch 218b, wire 321, and switches 221b and 219c, to wire 302. Upon magnet 212 being thus energized, switch 212a closes, thus establishing a connection from main take-off wire 303 through said switch 212a and wires 212l and 212m, to function in place of the above-enumerated connections between main take-off wire 303 and magnet 212, which connections will, of course, be broken as soon as die-carrier B starts moving outwardly, and thus permit switch B22 to open. Thus, through switch 212a the circuit through magnet 212 is maintained during the entire "out" movement of the die-carrier B.

Upon magnet 212 becoming energized, and during the period when it is held energized as just explained, switch 212b is opened, and held open, thus establishing a circuit through the "out" winding of the motor of die-carrier B, said cir-

cuit extending from main take-off wire 303 to wire 302 and including switch 212b, wire 322, the "out" winding of the motor of carrier B, wire 325, switch 232d (then held closed because of the fact that "out" magnet 232 is then energized, and is held energized through the entire "out" movement of any die-carrier), and wire 326.

Upon the said circuit being established through the said "out" winding of the motor of carrier B, 10 the latter starts moving outwardly, opening dog-actuated switches B42 and B22 and closing dog-actuated switch B12. Upon die-carrier B reaching its outermost position, dog B1 opens switch B11 and dog B3 closes switch B21, thus restoring 15 the electric connections of die-carrier B to the same state as the connections of the other five die-carriers of the press.

In order to fully understand the complete automatic functioning of the press disclosed in the 20 present application, let us assume that after die-carrier B has been started into the press at the beginning of its operating cycle, the operator in charge of die-carrier A, upon completing the loading of the dies thereon, presses selector 25 button switch 305. The pressing of said button switch completes a circuit through and energizes magnet 201 in the same manner as the pressing of the selector button switch 306 by the operator of die-carrier B energized magnet 202 at the beginning of the operating cycle of carrier B.

The effect of such selection of carrier A, however, cannot function immediately to energize magnet 211 in order to operate carrier A, for the reason that a circuit through the latter magnet 35 to energize it may only be initiated through selection-maintaining take-off wire 315, which, while carrier B remains in the press, is dead, due to the fact that switch 217e, in the circuit through said wire 315, is held open because magnet 217 is energized during the entire period when carrier B or any other carrier is in the press. However, as soon as carrier B reaches its outermost position in the cycle of operations just described, dog B1 engages and opens switch B11, thereby de-energizing magnet 217 and closing switch 217e. Therefore, in view of the fact that carrier A has 40 been pre-selected as the next carrier to go into the press, and as such pre-selection has been primarily established in magnet 201, the closing of switch 217e in the manner just described completes a circuit from main take-off wire 303 through said switch 217e, wire 315, wire 316, switch 201c, wire 211l, magnet 211, wire 211n, switches 212c, 213c, wire 320, switch 218b, wire 321, and switches 221b and 219c, thus energizing magnet 211 and closing switch 211b in the circuit through the "in" winding of the motor of die-carrier A, so that, immediately upon die-carrier B reaching its outermost position, die-carrier A automatically starts moving inwardly. Thereafter, the function of the various parts of the electric circuit to control the movement of die-carrier A into and out of the press is the same as has already been described with respect to die-carrier B.

It is to be understood, of course, that all of the die-carriers have similar electric apparatus and wiring controlling their operation, so that the 70 foregoing description of the operation of die-carrier B and of the manner in which die-carrier A would automatically function upon the completion of the outward movement of die-carrier B should suffice as an illustration of the mode of operation involved where other die-carriers are

substituted as the dies carried thereon are loaded with blanks and thus made ready for the pressing operation.

Automatic means have been provided for controlling the rotation of the dial 74 as different die-carriers go into the press, in order that the pad-holder 70 and the pad 69 therein may mate and coact properly with any die-carrier and dies thereon which may be in the press. The dial-controlling means referred to are such that when dial 74 is in one position, as, for example, in the position shown in Fig. 11c wherein the pad-holder 70 is in line with either die-carrier A or die-carrier D, the four dogs w, x, y, z are respectively engaging switch FR which controls right movement of the dial if carrier F is the next one selected to go into the press, switch EL which controls left movement of the dial if carrier E is the next one selected to go into the press, switch CR which controls right movement of the dial if die-carrier C is the next one selected to go into the press, and switch BL which controls left movement of the dial if carrier B is the next one selected to go into the press.

Of course, when the pad-holder is in the position indicated in Fig. 11c in full lines, it is obvious that if either die-carrier A or die-carrier D is the next one selected to go into the press, no movement whatever of the dial would be needed because it is already in line with either of the two last-mentioned die-carriers. Hence, with the dial in the position indicated in the drawing, none of the dogs w, x, y, z is in engagement with any switch which is adapted to function when either die-carrier A or die-carrier D is to go into the press.

If the dial 74 and the pad-holder 70 are in the positions indicated in Fig. 11c because of either die-carrier A or die-carrier D having been in the press, and if the next carrier to be used in a pressing operation is either die-carrier B or die-carrier E, it will be seen that, in order to bring the pad-holder 70 into line with either of the two last-mentioned die-carriers, it is only necessary to rotate the dial 60° to the left, and this is accomplished through either a circuit controlled by then-closed switch BL if die-carrier B is the next one to go into the press, or a circuit controlled by then-closed switch EL if die-carrier E is the next one to go into the press.

It may be observed that the circuits controlled by the two last-mentioned switches are circuits which, as will hereinafter be explained, control left movement of the dial. It should also be observed that if the dial is moved to the left in connection with the substitution of dies just mentioned, a minimum movement thereof is caused, in order to bring it into the newly selected pressing position, namely, 60°, while, were it to be moved to the right, a rotation of 120° would be necessary to bring the dial into such selected pressing position. If, however, it is desired that the next die-carrier to go into the press be either carrier C or carrier F, it will be perceived that the pad-holder 70 need be rotated only 60° to the right, rather than 120° to the left. Such right movement of the dial would be accomplished through the functioning of a circuit controlled by switch CR if carrier C were to be the next one to go into the press, or a circuit controlled by switch FR if carrier F is to be the next one to go into the press.

It may be seen, from Fig. 11c, that when the dial 74 comes to rest for a pressing operation involving any die-carrier, the switches then held

closed by the dogs w, x, y and z will always be those of which, upon the selection of the next die-carrier to go into the press, one will cause movement of the dial in whichever direction will cause the latter to move only through an angle of 60° in order to bring the pad-holder into alignment with the next carrier to be used.

With this preliminary insight into the purpose of the switches AL, AR, BL, BR, etc., the operation of the dial and the manner in which it is moved so that the pad-holder 70 may cooperate with any selected die-carrier may be more easily understood.

In considering the operation of the dial 74, it may be assumed that, in the last previous use of the press, die-carrier D was used and then withdrawn from the press, so that all of the die-carriers are in their outermost positions and the pad-holder 70 is in the position indicated in full lines in Fig. 11c. It may also be assumed that the same cycle of operation of the press is to take place as the cycle hereinbefore referred to in describing the operation of the various die-carriers. It is apparent that when the operator of die-carrier B pressed selector button switch 306 and

thereby energized magnet 202, the latter closed switch 202d, thus completing a circuit from main take-off wire 303 to wire 302 through switch 217e (then closed because magnet 217 is only energized when a die-carrier is in other than its outermost position), wire 315, switch 202d, wire 332, switch B1 (then closed by contact with dog z), wires 234n and 234m, "left" magnet 234, thence through switches 233b, 209b, 221b and 219c, all of which latter switches, as then controlled by their respective operating magnets, being in closed positions.

Upon "left" magnet 234 becoming energized, switch 234a closes and establishes a circuit from main take-off wire 303 through said switch 234a, wire 333, the "left" winding of the motor 82, wire 334, and thence through then-closed switches 209b, 221b and 219c, to wire 302. With the completion of the circuit through the "left" winding of the motor 82, the dial 74 starts moving to the left, which is the direction of movement by which it can reach a position wherein the pad-holder 70 is in line with selected die-carrier B with the least possible angular movement. As the dial turns to the left, dog z of course disengages and opens switch BL, but the circuit through the motor 82 is nevertheless maintained because of the fact that "left" magnet 234, having once become energized, closes and holds switch 234a closed, and, through the latter switch, the circuit through the motor 82 is maintained even after switch BL opens.

As the dial 74 continues to move to the left, one of the dogs 108 will, of course, engage the arm of switch SR, but, as said switch operates only upon right movement of the dial, such engagement of said switch produces no effect whatever. The dial 74 thus continues to move to the left until, just before completing a rotation of 60°, switch SL is momentarily actuated by one of the dogs 107. The momentary actuation and closing of switch SL completes a circuit through magnet 209, from take-off wire 303 to wire 302, including wire 209l, switch SL, wire 209p, and magnet 209, thereby energizing the latter. Upon magnet 209 thus becoming momentarily energized, switch 209b in the circuit through the motor 82 momentarily opens, and during that moment "left" magnet 234 is de-energized and switch 234a opens, thus breaking the circuit

through motor 82 and causing the dial 74 to stop rotating.

The coasting of the motor 82 will cause the dog 107 to pass over and become disengaged from switch SL, whereupon magnet 209 again becomes de-energized and switch 209b closes; but the closing of the latter switch does not complete a circuit through the motor 82, for the reason that both switches 233a and 234a are open, and, in consequence, no circuit may be again established in the motor 82 until one of the pre-selection buttons 305, 306, etc., has been pressed, thereafter, in order to establish a new selection for either right or left rotation of the dial 74 through the switches AL, AR, BL, BR, etc.

It should be noted that, if the dial comes to rest in the precise position in which it may coact properly with the selected die-carrier in a pressing operation, the switch DS is held closed by one of the dogs 108 and thus forms part of the circuit through magnet 221 so that the latter may be energized and cause the press to close in the manner already explained. If, however, the dial does not come to rest in the precise pressing position desired, no one of the dogs 108 will be in position to close switch DS, and hence the press cannot be closed in the manner described, unless the dial is first moved to such precise pressing position. It may also be noted that while the press is closing and opening, switches 219c and 221b are open, and hence during the closing and opening of the press no movement of the dial 74 can take place.

If, in the described cycle of operation of the die-carriers, selector button switch 305 is pressed and closed by the operator of carrier A before the carrier B pressing operation is completed, switch 201d immediately closes but a circuit, through motor 82 to effect a further movement of the dial to the right to cause the latter to mate with carrier A, can only be completed upon closing of switch 219c upon the completion of the upstroke of the press slide 24 at the termination of the carrier B pressing operation. Under such conditions, the dial 74 rotates to the right toward mating position with respect to carrier A, during the movement of carrier B out of the press. However, if the button switch 305 is not pressed and closed until after the press opens at the termination of the carrier B pressing operation, switch 219c at that time is in closed position; hence, the rotation of the dial, toward mating position with respect to carrier A, commences immediately upon closing of said switch 305. The electric apparatus controlling rotation of the dial functions similarly with respect to any die-carrier which may be selected to go into the press.

It will be understood from the foregoing description that the press and the controlling apparatus disclosed herein are fully automatic in operation, inasmuch as an operator need only press a selector button switch to bring into complete operation, in proper sequence and without conflict, all moving parts of the press and all electric apparatus controlling the movement of such parts.

Without attempting to enumerate all the variations which might be employed within the scope of the present invention, it may be observed that the invention could be applied to mechanical presses or to hydromechanical presses as well as to hydraulic presses; also, that it could be applied by employing multi-speed motors both on the die-carriers and on the dial; also, that the press

itself might function on two or more speeds on the closing stroke of the press and possibly on several speeds on the opening stroke of the press. As the present disclosure is purely illustrative, the foregoing and other variations may be employed without departing from the spirit of the invention.

What I claim is:

1. A press comprising a pair of members, one of which is movable relatively to the other to perform a pressing operation, die-guiding and holding means, on one member of said pair, adapted to guide oblong die assemblies separately into different angular pressing positions and to hold any one of such assemblies in its said pressing position, and a resilient oblong pressing member, substantially conforming to the oblong shape of such die assemblies and being rotatably mounted upon the other member of said pair, the rotatability of said resilient member being such as to permit the latter to be rotated into mating alignment with a die assembly carried in any one of such angular pressing positions.

2. A press comprising a bed, a plurality of oblong die-carriers each separately movable into a different radial pressing position upon said bed, a slide movable toward said bed to perform a pressing operation, and a resilient, oblong pressing member substantially conforming to the oblong shape of said die-carriers and being rotatably mounted upon said slide, said resilient member being adapted to be rotated to bring it into mating alignment with any one of said die carriers which is in pressing position upon said bed.

3. A press comprising a pair of members, movable relatively to each other to perform a pressing operation, a plurality of movable, oblong die-carriers, each adapted for movement separately into a different angular pressing position on one of said pair of members, and a resilient oblong pressing member mounted upon and movable relatively to the other of said pair of members, the mobility of said resilient member being such as to permit the oblong contour of the latter to be brought into mating alignment with the oblong contour of any one of said die-carriers which may be moved into pressing position.

4. A press comprising a pair of members, one of which is movable relatively to the other to perform a pressing operation, a plurality of movable oblong die-carriers, each adapted for movement separately into a different angular pressing position on one of said pair of members, and a resilient oblong pressing member rotatably mounted upon the other of said pair of members, the rotatability of said resilient member being such as to permit the oblong contour of the latter to be rotated into mating alignment with the oblong contour of any one of said die-carriers which may be moved into pressing position.

5. A press comprising a bed, a plurality of movable oblong die-carriers, radially arranged about said bed, and each adapted for movement radially into a different radial pressing position on said bed, a slide movable toward said bed to perform a pressing operation, and a resilient oblong pressing member rotatably mounted upon said slide, said resilient member being adapted to be rotated to bring its oblong contour into mating alignment with the oblong contour of any one of said die-carriers which may be moved into pressing position on said bed.

6. A press comprising a pair of members, movable relatively to each other to perform a pressing operation, a plurality of movable die-carriers, each adapted for movement separately from a non-pressing position into a pressing position on one of said pair of members, and control means for controlling the movement of said carriers, the said means including operating members adapted to coact with and be operated by each die-carrier only when the latter is in non-pressing position, such operation of all said operating members being necessary to render said control means effective for initiating movement of any one die-carrier from its non-pressing position toward its pressing position.

7. A press comprising a pair of members, movable relatively to each other to perform a pressing operation, a plurality of movable die-carriers, each adapted for movement separately from a non-pressing position into a pressing position on one of said pair of members, and control means for controlling the movement of said carriers, the said control means including means for initiating the movement of each of said die-carriers, and an operating control member, common to the latter means of all said die-carriers, the said movement initiating means of each die-carrier being adapted to operate the said control member whereby to render ineffective the movement initiating means of all other die-carriers and thereby prevent simultaneous movement of any other die-carrier.

8. A press comprising a pair of members, movable relatively to each other to perform a pressing operation, a plurality of movable die-carriers, each adapted for movement separately into a pressing position on one of said pair of members, primary control means for moving said carriers, and secondary control means for preventing simultaneous movement of more than one of said carriers, the said primary control means comprising separate circuits for controlling the movement of each of said die-carriers and the said secondary control means comprising connections, in each of said circuits, controlled by each of the other of said circuits and adapted to be opened when any one of such other circuits is closed, whereby when any one of the circuits comprising said primary control means is closed to move its related die-carrier, all other such circuits are necessarily open and their related die-carriers prevented from moving.

9. A press comprising a pair of members, movable relatively to each other to perform a pressing operation, a plurality of movable die-carriers, each adapted for movement separately into a pressing position on one of said pair of members, primary control means for moving said carriers, and secondary control means for preventing simultaneous movement of more than one of said carriers, the said primary control means comprising separate circuits for controlling the movement of each of said die-carriers and the said secondary control means comprising relays in each of said circuits, and switches, controlled by said relays, in each of the other of said circuits, the control of said switches by said relays being such that when one of said circuits is closed to move its related die-carrier and, in consequence, the relay in said circuit is energized, the switches, controlled by said energized relay, in all the other said circuits, are opened and held open whereby to prevent movement of all die-carriers controlled by such open circuits.

10. In a press comprising a pair of members, movable relatively to each other to perform a pressing operation, in combination, a resilient oblong pressing member rotatably mounted upon one of said pair of members, controlling means for controlling the rotation of said resilient member to various pressing positions in which it may be in mating alignment with an oblong die assembly carried in any one of plural angular pressing positions at a single pressing station upon the other of said pair of members, and means, actuated independently of said resilient pressing member for selecting the pressing position to which the said resilient member is to be rotated, the latter means coacting with the said controlling means whereby to cause the said resilient member to rotate to the selected pressing position.

11. In a press comprising a pair of members, movable relatively to each other to perform a pressing operation, in combination, a resilient oblong pressing member rotatably mounted upon one of said pair of members, and controlling means for controlling the rotation of said resilient member to various pressing positions in which it may be in mating alignment with an oblong die assembly carried in any one of plural angular pressing positions at a single pressing station upon the other of said pair of members, said controlling means comprising separate circuits for controlling the rotation of said resilient member from each of its various pressing positions to each of its other pressing positions, separate switches in each of said circuits for partially controlling the latter, those of said switches which are in said circuits controlling such rotation from each pressing position being adapted to coact with the resilient pressing member whereby to partially complete such circuits controlling such rotation to all other pressing positions, and means actuated independently of said resilient pressing member for selecting the pressing position to which the said resilient member is to be rotated and for completing the one of said circuits controlling such rotation to the selected pressing position.

12. In a press comprising a pair of members, movable relatively to each other to perform a pressing operation, in combination, a resilient oblong pressing member mounted upon one of said pair of members and adapted to be rotated in opposite directions, and controlling means for controlling the rotation of said resilient member whereby to cause the latter to move, in whichever direction may bring it, with a minimum of rotative movement, to a selected new pressing position in which it may be in mating alignment with an oblong die assembly carried in a particular angular position at a single pressing station upon the other of said pair of pressing members, the said controlling means including an operating member constituting means for partially controlling the initiation of rotation of the said resilient member in one direction from a first to a second pressing position, and another operating member constituting means for partially controlling the initiation of rotation of the said resilient member in the opposite direction from said first to a third pressing position, both said operating members being adapted to coact with and be operated by said resilient member when the latter is in the said first pressing position whereby to be in condition to participate in the initiation of rotation of the resilient pressing member to whichever of the said second or

third pressing positions it may be desired to rotate the said resilient member.

13. In a press comprising a pair of members, movable relatively to each other to perform a pressing operation, in combination, a resilient pressing member mounted upon one of said pair of members and adapted to be rotated in opposite directions, and controlling means for controlling the rotation of said resilient member whereby to cause the latter to move, in whichever direction may bring it, with a minimum of rotative movement, to a selected new pressing position in which it may be in mating alignment with a die carried in a particular position upon the other of said pair of pressing members, said controlling means comprising two separate circuits for controlling the rotation of said resilient member to each of its various pressing positions, one of said two circuits being adapted to control such rotation in one direction and the other of said two circuits being adapted to control such rotation in the opposite direction, primary means for partially completing, as to each of the various pressing positions to which the said resilient member may be moved, the said circuit controlling rotation of said member in the direction in which minimum rotative movement may bring said member to such pressing position, and secondary means for completing, as to each of such various pressing positions, the one such partially completed circuit which controls rotation of said resilient member to that particular pressing position.

14. In a press comprising a pair of members, movable relatively to each other to perform a pressing operation, the combination according to claim 13, the said primary means comprising switches in each of said circuits, and means movable with said resilient member, adapted, as to each new pressing position to which said member may be rotated, to actuate the said switch in whichever circuit controls such rotation in that direction in which minimum rotative movement may bring said member into such new pressing position.

15. In a press comprising a pair of members, movable relatively to each other to perform a pressing operation, the combination according to claim 13, the said primary means comprising dog-actuated switches, in each of said circuits, disposed circumferentially about the path of movement of said pressing member, and one or more dogs, constrained to rotate with said pressing member and, as to each new pressing position to which said member may be rotated, adapted to actuate the said switch in whichever circuit controls such rotation in that direction in which minimum rotative movement may bring said member into such new pressing position.

16. In a press comprising a pair of members, movable relatively to each other to perform a pressing operation, the combination according to claim 13, the said primary means comprising dog-actuated switches, in each of said circuits, disposed circumferentially about the path of movement of said pressing member, and one or more dogs, constrained to rotate with said pressing member and, as to each new pressing position to which said member may be rotated, adapted to actuate the said switch in whichever circuit controls such rotation in that direction in which minimum rotative movement may bring said member into such new pressing position, the said switches and the said dog or dogs being so positioned that when the said resilient member

is at rest in any of its various pressing positions, the said switch or switches, in circuits controlling the direction of minimum rotation to various other pressing positions, are held actuated by one or more of said dogs so that upon any one of said circuits being completed through the functioning of said secondary means, the resilient pressing member will be caused to rotate in the direction requiring minimum rotation to move said resilient pressing member to the particular new pressing position.

17. A press comprising a pair of members, movable relatively to each other to perform a pressing operation, a plurality of movable die-carriers, carrier control means for controlling the movement of said carriers, each into a different pressing position on one of said pair of members, a resilient pressing member movably mounted upon the other of said pair of members, pressing member control means for controlling the movement of said pressing member to various pressing positions corresponding to the said pressing positions of the several die-carriers, and separate selection means for each die-carrier, each including an operating member of the said carrier control means and an operating member of the said pressing member control means, which operating members included in each said selection means are adapted to participate in the operation of said two control means whereby to control the movement of a related die-carrier into pressing position and of the resilient pressing member to a pressing position corresponding to that of said selected carrier.

18. A press comprising a pair of members, movable relatively to each other to perform a pressing operation, a plurality of movable die-carriers, carrier control means for controlling the movement of said carriers, each into a different pressing position on one of said pair of members, a resilient pressing member movably mounted upon the other of said pair of members, pressing member control means for controlling the movement of said pressing member to various pressing positions corresponding to the said pressing positions of the several die-carriers, and selection means for initiating movement of a selected carrier to a pressing position, and said pressing member to a corresponding pressing position, said selection means being substantially similarly connected to said carrier control means, with respect to each carrier, and to said pressing member control means with respect to each pressing position thereof corresponding to pressing positions of the several carriers, whereby operation of said selection means, to move a selected carrier into pressing position, causes said pressing member to move to a corresponding pressing position, or, if already in such position, causes it to remain so.

19. A press according to claim 18, the said selection means comprising separate relays in selection circuits related to each die-carrier, the said carrier control means comprising separate control circuits controlling the several die-carriers, the said pressing member control means comprising separate pressing member control circuits controlling movement of the pressing member to the several pressing positions thereof, there being provided, with respect to the control circuit of each said carrier, a separate, related pressing member control circuit controlling movement of said member to a pressing position corresponding to that of said carrier, and

said related control circuits each having a switch therein adapted to be operated by the said relay in the selection circuit related to the die-carrier.

20. A press comprising a pair of members, movable relatively to each other to perform a pressing operation, a plurality of pairs of oppositely disposed, movable die-carriers arranged radially about a first member of said pair of members, carrier control means for controlling the movement of said carriers of each pair, at different times, into a common pressing position on said first member different from the pressing positions of the other carriers, a resilient pressing member rotatably mounted upon a second member of said pair of members, pressing member control means for controlling the rotation of said pressing member to various pressing positions corresponding to the pressing positions of the several pairs of die-carriers, and separate selection means for each die-carrier, each including an operating member of the said carrier control means and an operating member of the said pressing member control means, which operating members included in each said selection means are adapted to participate in the operation of said two control means whereby to control the movement of a related die-carrier into pressing position and of the resilient pressing member to a pressing position corresponding to that of said selected carrier.

21. A press comprising a pair of members, movable relatively to each other to perform a pressing operation, a plurality of pairs of oppositely disposed, movable die-carriers arranged radially about a first member of said pair of members, carrier control means for controlling the movement of said carriers of each pair, at different times, into a common pressing position on said first member different from the pressing positions of the other carriers, a resilient pressing member rotatably mounted upon a second member of said pair of members, and pressing member control means for controlling the rotation of said pressing member to various pressing positions corresponding to the pressing positions of the several pairs of die-carriers, and separate selection means for each die-carrier, each including an operating member of the said carrier control means and an operating member of the said pressing member control means, which operating members included in each said selection means are adapted to participate in the operation of said two control means whereby to control the movement of a related die-carrier into pressing position and of the resilient pressing member to a pressing position corresponding to that of said selected carrier, the said pressing member control means, further, being adapted to rotate the pressing member in whichever of two opposite directions of rotation will cause the pressing member to assume such last-mentioned pressing position with the least rotational movement.

22. A press comprising a pair of members, movable toward each other to close the press for a pressing operation, an oblong rotatable resilient pressing member, on one of said pair of members, adapted to be rotated in either direction to a plurality of pressing positions to bring it into mating alignment with an oblong die assembly carried in any one of a plurality of angular pressing positions at a single pressing station, and closing means for closing the press, the said closing means being so interconnected with the proper pressing positions of

said pressing member, that said means may not function to close the press unless the said pressing member is in one of its proper pressing positions.

5 23. A press comprising a pair of members, movable toward each other to close the press for a pressing operation, an oblong rotatable resilient pressing member, on one of said pair of members, adapted to be rotated in either direction to a plurality of pressing positions to bring it into mating alignment with an oblong die assembly carried in any one of a plurality of angular pressing positions at a single pressing station, and closing means for closing the press, said means comprising a circuit, controlling the closing movement of the press, and said circuit including a switch adapted to be engaged and actuated by the said pressing member, whereby to permit closing of the press, only when the said pressing member is in one of its proper pressing positions.

10 24. A press comprising a pair of members, movable toward each other to close the press for a pressing operation and movable away from each other to open the press, an oblong rotatable resilient pressing member, on one of said pair of members, adapted to rotate in either direction to various pressing positions to bring it into mating alignment with an oblong die assembly carried in any one of a plurality of angular pressing positions at a single pressing station, and means for preventing any such rotation except when the press is open.

15 25. A press comprising a pair of members, movable toward each other to close the press for a pressing operation and movable away from each other to open the press, an oblong rotatable resilient pressing member, on one of said pair of members, adapted to rotate in either direction to various pressing positions to bring it into mating alignment with an oblong die assembly carried in any one of a plurality of angular pressing positions at a single pressing station, and means for preventing any such rotation except when the press is open, said means comprising a circuit, controlling such rotation, and a switch in said circuit, controlled by the movement of a movable member of said pair of members and adapted to operate, to cause said circuit to function to rotate the said pressing member, only when the press is open.

20 26. A press comprising a pair of members, movable toward each other to close the press for a pressing operation and movable away from each other to open the press, a plurality of oblong die-carriers, each adapted to move between a different inoperative position and a different pressing position at a single pressing station on one of said pair of members, a rotatable pressing member, on the other of said pair of members, adapted to rotate in either direction to various pressing positions to bring it into mating alignment with whichever of said carriers may be in pressing position, and means for preventing any carrier movement or pressing member rotation except when the press is open, said means comprising circuits, controlling such movement and rotation, and a switch, controlling said circuits, and controlled by the movement of a movable member of said pair of members and adapted to operate, to cause said circuits to function to move the die-carrier and rotate the pressing member, only when the press is open.

25 27. A press comprising a plurality of die-carriers movable separately into pressing posi-

tions in the press, separate manually-controlled selection relay circuits for each of said die-carriers, a selection-controlling relay circuit for preventing operation of more than one of said manually-controlled circuits at one time, separate selection-maintaining relay circuits for each of said die-carriers, and separate actuating circuits for each of said die-carriers, the said selection-controlling circuit having switches therein, operated by relays in said manually-controlled circuits and the said manually-controlled circuits having a switch therein, operated by a relay in said selection-controlling circuit, whereby to prevent operation of more than one said manually-controlled circuit at a time, the said selection-maintaining circuit of each carrier having a switch therein operated by a relay in the manually-controlled circuit of the corresponding carrier, and the said actuating circuit of each carrier having a switch therein operated by a relay in the selection-maintaining circuit of the corresponding carrier, whereby the operation of a manually-controlled selection circuit of a selected carrier operates through said selection-maintaining and actuating circuits of that carrier to actuate the latter.

28. A press according to claim 27, further comprising a rotatable pressing member adapted to rotate to pressing positions corresponding to those of the several die-carriers, and separate pressing member actuating circuits for each of the positions to which said member may be rotated, each of said latter circuits having switches therein, operated by a relay in the manually-controlled circuit of a corresponding die-carrier, whereby the operation of the latter circuit causes said pressing member to rotate to its pressing position corresponding to that of the die-carrier being operated.

29. A press comprising a plurality of die-carriers movable separately from inoperative positions into operative pressing positions in the press, separate reversible motors for moving each of said carriers, separate circuits through each of said motors for reversibly operating the latter in opposite directions toward each of said positions, two direction-control circuits, each adapted to partially control the movements of any of said carriers, one being adapted to control such movement in one direction and the other being adapted to control movement in an opposite direction, and switches, coacting with each carrier, operated by the latter's movement, and adapted to control the said direction-control circuits whereby to adapt the said motor circuits to operation of the carriers in opposite directions.

30. In a press, the combination comprising a bed, a vertically reciprocable slide adapted to coact with said bed to perform a pressing operation, closing means for moving said slide toward said bed, opening means for moving said slide away from said bed, reversing means for reversing such slide movement from closing to opening movement, a plurality of movable die-carriers radially supported about said bed, separate reversible moving means for each of said carriers adapted to move the latter back and forth between outer or inoperative positions and inner or operative positions in which latter positions said carriers are in pressing positions upon said bed, a resilient pressing member, carried on said slide and adapted to rotate to pressing positions corresponding to those of the die-carriers, and rotating means for effecting such rotation, each of said carriers and said pressing member being

adapted, upon substantially reaching their respective pressing positions, to coact with said closing means whereby to initiate the closing of the press and the said press slide being adapted, 5 upon substantially reaching its open position, to coact with said carrier moving means whereby to initiate movement of a carrier, then in pressing position, from the latter position toward its inoperative position, the said carrier moving 10 means and the said rotating means being so interconnected that any selected carrier and said pressing member move automatically to corresponding pressing positions prior to the closing of the press.

15 31. In a press, the combination according to claim 30, the said pressing member being rotatable in opposite directions, and the said rotating means being interconnected with said carrier moving means and adapted, through such interconnection, to move concurrently with any selected carrier, to a pressing position corresponding to that of such selected carrier, in whichever of such opposite directions will bring said pressing member to such corresponding pressing position with least rotation of said member.

20 32. A machine tool comprising a pair of members, movable toward each other to perform a mechanical operation upon a blank disposed therebetween, a plurality of blank-carriers disposed in plural non-parallel radial positions about one of said members and adapted to move separately, from different ones of said positions thereabout, into different angular positions relatively to said one member, and a tool-carrying operating head mounted upon the other member of said pair, the said operating head being rotatable relatively to said other member whereby to bring a tool carried by said head into a predetermined operating alignment relatively to a blank-carrier 25 disposed in any one of the mentioned different angular positions.

30 33. A machine tool comprising a fixed member, a movable member, movable toward said fixed member to perform a mechanical operation upon a blank disposed therebetween, a plurality of blank-carriers disposed in plural non-parallel radial positions about said fixed member and adapted to move separately, from different ones of said positions thereabout, into different angular 35 positions upon said fixed member, and a tool-carrying operating head mounted upon the said movable member, the said operating head being rotatable relatively to said movable member whereby to bring a tool carried by said head into a predetermined operating alignment relatively to a blank-carrier disposed in any one of the mentioned different angular positions.

34. A press comprising a pair of members, movable toward each other to perform a pressing operation upon a blank disposed therebetween, a plurality of die-carriers disposed in plural non-parallel radial positions about one of said pair of members and adapted to carry dies separately, from different ones of said positions thereabout, into different angular positions relatively to said one member, and a pressing head carrying a pressing element and being mounted upon the other member of said pair, the said pressing head being rotatable relatively to the said other member whereby to bring the pressing element carried by said head into a predetermined pressing alignment relatively to a die carried in any one of the said different angular positions on the first mentioned one of said pair of members.

35. A press comprising a bed, a plurality of die-

carriers disposed in plural non-parallel radial positions about said bed and adapted to carry dies separately, from different ones of said positions thereabout, into different angular pressing positions relatively to said bed, a slide movable toward said bed to perform a pressing operation, and a pressing head carrying a pressing element and being mounted upon said slide, the said pressing

5 head being rotatable relatively to said slide whereby to bring the pressing element carried by said head into a predetermined pressing alignment relatively to a die carried in any one of the said different angular positions on the said bed of the press.

EARL CANNON.
